Application August 3, 1949, Serial No. 108,397

7 Claims. (Cl. 270—53)

1

This invention relates to book stitching machines of the type wherein a group of nested signatures is stitched together by wire staples and refers particularly to the delivery mechanism thereof.

Such stitching machines generally comprise a signature collecting and conveying chain movable past, or more directly under, a series of loading stations upon which the individual signatures are placed. Pushers mounted on the chain at spaced intervals strip the signatures off the loading stations and gather them into groups. The groups of signatures thus gathered are advanced by the chain to a saddle where grippers present them to stitcher heads. The stitcher heads drive a suitable number of wire staples into each group of signatures and the books thus formed are advanced further along the saddle to a delivery mechanism which deposits them in a seriated bank upon a table provided with intermittently moving tapes or belts.

Inasmuch as this invention is concerned chiefly with the delivery mechanism it embodies some of the structure disclosed in Patent No. 1,879,040 issued September 27, 1932, to Elmer W. Belluche. In that patent the intermittent advance of the tapes of the delivery table was coordinated with the delivery of the stitched books so that the bank of books on the delivery table would remain at rest during those cycles of the machine when no book was discharged from the machine. This assured uniform spacing between the edges of the books on the delivery table.

To effect this result the aforesaid patent provided a feeler which felt for the stitched books as they were about to be delivered, and mechanism controlled by the feeler governed the operation of the means for intermittently advancing the tapes of the delivery table.

The present invention also coordinates the intermittent advance of the books on the delivery table with the delivery of the stitched books; but in addition utilizes the same feeler which effects this coordination for preventing elevation of the tucker blades (by which the stitched books are lifted off the saddle into the bite of the delivery rolls) except when a fully stitched book is in proper position for delivery.

In other words, this invention contemplates the provision of means for making the elevation of the tucker blades dependent upon the presence of a stitched book in proper position for delivery. By this means, as will appear more fully hereinafter, the present invention greatly simplifies adapting the machine to book lengths

2

requiring "two-up," "three-up" or even "four-up" operation. These terms are well known in the industry so that for those skilled in the art no explanation is needed. However, it may be briefly noted that with "one-up" work a book is stitched and delivered each cycle while with "two-up" work two cycles are required to stitch one book and a book is delivered only every other cycle, and "three-up" operation requires three cycles for each book. Books are seldom longer than a length which can be handled with "three-up" operation, but in each instance where the book exceeds the length which can be handled with "one-up" operation, the leading end of the book is stitched during one cycle and the trailing end of the book is stitched during the next cycle or, if necessary, three or perhaps four cycles of the machine may be allocated to the stitching of a single book. In this manner the scope of the work which can be handled by the machine is materially increased and in addition the machine is not as susceptible to shutdown as a result of failure of one of the stitcher heads, which often happens.

Obviously to enable such stepwise stitching of the books it is essential that the tucker blades be restrained from elevation until the fully stitched book is wholly within the delivery. In the past this entailed changing cams and adjusting other mechanism, whereas with the present invention, switching from one type of operation to another, as for instance from "one-up" to "two-up" work requires merely shifting the location of the feeler.

As noted hereinbefore, the delivery belts or tapes which collectively provide an apron onto which the stitched books are discharged, are intermittently advanced so that the stitched books lay thereon in a seriated row or bank. Operators remove the books from the discharge end of the delivery table, and to facilitate keeping count of the books this invention provides means for increasing the advance of the delivery belts at stated intervals so as to periodically effect wider spaces between the books disposed thereon.

This increased advance of the delivery belts to facilitate counting, as well as the regular intermittent advance of the delivery belts, of course, must be coordinated with the discharge of books from the machine, more specifically from the saddle of the machine, and to assure such coordination, it is another object of this invention to govern the operation of the mechanism effecting these three functions—viz. removal of the stitched books from the saddle, regular inter-

mittent advance of the delivery belts, and periodic long advance of the delivery belts—all from the same feeler.

With the above and other objects in view, which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate one complete example of the physical embodiment of the invention constructed according to the best mode so far devised for the practical application of the principles thereof, and in which:

Figure 1 is a front view of the delivery mechanism of a signature stitching machine embodying this invention with parts thereof broken away, said view showing the parts in the positions they occupy just before the tucker blades lift the stitched book into the bite of the delivery rolls; 10

Figure 1A is an enlarged fragmentary detail view illustrating the feeler in position engaging a stitched book on the saddle;

Figure 2 is a view similar to Figure 1 but showing the parts in the positions occupied the instant of maximum elevation of the tucker blades, with the stitched book lifted thereby in the bite 20

of the delivery rolls, and the feeler lifted;

Figure 3 is a view similar to Figure 1 but showing the parts in the positions occupied when no book is in position to prevent full descent of the feeler, so that the delivery mechanism, including the tucker blades, is held inoperative;

Figure 4 is a view similar to Figure 3 but illustrating the mechanism advanced slightly beyond the position shown in Figure 3 with the feeler lifted but the latch which holds the mechanism 30

inoperative still engaged;

Figure 5 is a sectional view through Figure 1 on the plane of the line 5—5;

Figure 6 is a top plan view of the mechanism shown in the previously identified views;

Figure 7 is a perspective view of the mechanism with the individual elements thereof separated to more clearly indicate their functional relationship;

Figure 8 is a cross sectional view through the delivery table illustrating the double pawl belt advancing mechanism;

Figure 9 is a view similar to Figure 8 but illustrating the parts at an instant in the cycle of the machine just after that shown in Figure 8 50

with the pawl which advances the delivery belts with the long step engaged and about to effect such advance;

Figure 10 is a view similar to Figures 8 and 9 built with the parts in the positions occupied directly after the long advance of the delivery belts;

Figure 11 is a detail sectional view through Figure 10 on the plane of the line 11—11 illustrating the manner in which the long advance of the delivery belts is precluded except at predetermined widely spaced intervals; and

Figure 12 is a diagrammatic view illustrating the application of this invention to "two-up" work wherein two cycles of the machine are required to stitch one book and a book is delivered every 70

chine, adjacent to which most of the mechanism involved in this invention is located. Since the invention is not concerned with the signature gathering or the stitching means the entire machine has not been illustrated. For a disclosure of the type of machine to which the invention pertains reference may be had to Patents Nos. 1,314,503 issued September 2, 1919 and 1,716,773 issued June 11, 1929.

Extending from the end frame 4 is an inverted V-shaped saddle indicated generally by the numeral 5 along which the gathered signatures are advanced by gripper fingers 6 to stitcher heads (diagrammatically shown in Figure 12) where wire staples are driven into each group of signatures to stitch the same into a book. On the next succeeding cycle of the machine the book just stitched is advanced farther along the saddle towards the end frame 4 to a delivery position.

The saddle 5 comprises two angularly disposed front and back plates 7 and 8, the former having an elongated slot 9 extending lengthwise thereof near its top edge. The upper edges of these plates 7 and 8 are spaced apart to permit tucker blades 10 to pass upwardly therebetween and by this action lift a stitched book resting on the saddle in position for delivery into the bite of co-operating delivery rolls 11 and 12.

The delivery rolls 11 are carried by a shaft 13 which is journaled for rotation on a fixed axis, while the rolls 12 are carried by a shaft 14 adapted for lateral movement toward and from the shaft 13. For this purpose the shaft 14 is journaled in bearings carried by levers 15, only one of which is shown, mounted to turn about a stationary tie rod 16. A spring 17 connected to an arm 18 extending from one of the levers 15 yieldingly urges the rolls 12 toward the rolls 11.

Rotation is positively and continuously imparted to the delivery rolls through gearing shown in Figure 6. This gearing comprises a main gear 19 mounted on a power shaft 20 which is suitably driven from the machine. The main gear 19 meshes with a large gear 21 fixed to a cam shaft 22 and meshing with a gear 23 on the shaft 13. The gear 21 is also drivingly connected with a similar gear 24 fixed to the shaft 14 through an intermediate idler gear 25 so that the rolls 11 and 12 both rotate in the right direction. The idler gear 25 is mounted on a stub shaft fixed in the frame 4 substantially directly under the gear 24 so that lateral movement of the gear 24 as the rolls 12 move toward and from their companion rolls 11 will not disrupt the drive to the gear 24. The cam shaft 22 is journaled in a bearing carried by the end frame 4 and passes through the frame to mount the gear 21 at the inner face thereof and cams 26 and 27 at its outer face. As will appear more fully hereinafter, the cam 26 may be identified as a feeler cam and the cam 27 as a delivery cam.

The tucker blades 10 are mounted on a bar 28 extending lengthwise of the saddle at the delivery end thereof, and this bar 28 is normally raised and lowered once during each cycle of operation of the machine. Ascent of the bar 28 and the tucker blades 10 fixed thereto is effected impositively by spring means, not shown, while descent of the bar 28 and the tucker blades carried thereby is effected positively by a cam, not shown. The means for raising and lowering the tucker blades is thus similar to that employed in Patent No. 1,750,622 issued March 18, 1930, but contrary to past practice means are provided for restraining ascent of the bar 28 and the tucker blades

Referring now particularly to the accompanying drawings in which like numerals indicate like parts throughout the several views, the numeral 4 indicates the delivery end frame of the ma-

carried thereby except when a stitched book is in position to be delivered. This means comprises a latching finger 29 fixed to a shaft 30 and depending therefrom to be moved into and out of the path of an abutment 31 movable with the bar 28. Thus when the latching finger 29 is in its locking position as shown in Figures 1, 3 and 7, the tucker blades 10 will be restrained against ascent.

The latching finger is yieldingly urged into the path of the abutment 31 by a spring 32 (see Figures 1 and 2), one end of which is anchored as at 33 and the other end of which is connected to an arm 34 fixed to the shaft 30. The spring thus biases the shaft 30 in a clockwise direction tending at all times to hold the latching finger in the path of the abutment 31, this position being defined by the engagement of the side of the latching finger with the face of the tucker bar carrier 35 on which the abutment 31 is fixed.

Once each cycle the shaft 30 is oscillated in a counter-clockwise direction by the delivery cam 21, this action being so timed that the latching finger 29 is moved out of the path of the abutment 31 just before ascent of the tucker blades is to take place. However, if a book is not in position to be delivered, which fact is determined by a feeler 36 dropping down into the slot 9, the latching finger will be retained in its locking position restraining the tucker blades against ascent.

The feeler 36, which is preferably a wheel, is mounted on the outer end of an arm 37 fixed to but adjustable lengthwise of a shaft 38. This shaft extends along the length of the delivery portion of the saddle and is journaled in bearings 39 carried by brackets 40 depending from the frame 41 of the delivery table indicated generally by the numeral 42, only one of the brackets 40 and one of the bearings 39 being illustrated.

The end of the shaft 38 which protrudes from the bearing 39 illustrated and which, of course, is adjacent to the end frame 4 has a lever 43 fixed thereto and this lever has two arms 44 and 45, the former extending into the path of a roller 46 carried by a lever 47 and the latter being engageable by an adjustable abutment screw 48 carried by an arm 49 forming part of a bell crank lever 50 loose on the outer end of the shaft 38.

The other arm 51 of the bell crank lever is connected through a link 52 with a latch 53. The latch 53 is pivoted upon a stub shaft 54 fixed in the end frame 4 and overlies a combination latch bar and driving link 55. The top edge of this bar 55 has a notch 56 therein to provide a keeper recess into which the end of the latch 53 may drop to restrain endwise movement of the link 55 toward the right as viewed in Figure 1, such movement, if permitted, being imparted to the link 55 by a strong tension spring 57 connected to a compound lever 58.

The compound lever 58 is pivoted on a stub shaft 59 projecting from the frame 4, and has the link 55 connected to one arm 60 thereof as at 61. The spring 57 is connected to another arm 62 of the compound lever while a third arm 63 carries a cam follower roller 64 adapted to track upon and follow the delivery cam 27 provided the latch 53 is not engaged in the keeper recess 56.

A fourth arm 65 of the compound lever 58 has a cam shaped outer end engageable with a roller 66 on the arm 34 to rock the shaft 38 in a counter-clockwise direction and thereby swing the latching finger 29 out of the path of the abutment 31. It is to be noted, however, that the shaft 38 will

not be so rotated unless the latch 53 is disengaged from its keeper recess 56, and this in turn depends upon whether or not the feeler 36 has been permitted to drop down into the slot 9.

The shaft 38 is positively rocked in a clockwise direction by the feeler cam 26 acting through the levers 47 and 43, the former being pivoted upon the stub shaft 54 and carrying a roller 67 which tracks upon and follows the cam 26. A tension spring 68 having one end anchored as at 33 and its other end connected to the lever 47 as at 69 yieldingly holds the roller 67 in tracking engagement with the cam 26. As the cam rotates, its high point swings the lever 47 in a counter-clockwise direction to engage its roller 46 with the arm 44 of the lever 43 and against the tension of a spring 70 positively rock the shaft 38 in a clockwise direction. Such clockwise rotation of the shaft 38, of course, lifts the feeler 36 as shown in Figure 4 to permit the next succeeding book to be advanced to delivery position without having the feeler ride thereover.

As the cam 26 continues to rotate and the roller 67 rides down onto the low part of the cam, the spring 68 swings the lever 47 in a clockwise direction which allows the spring 70 to impositively turn the shaft 38 in a counter-clockwise direction to lower the feeler 36. As the shaft 38 rocks, the bell crank 50 which is loose thereon follows by virtue of its connection with the lever 43 afforded by a spring 86 reacting against the screw 48, and as a result effects engagement of the latch 53 in its keeper recess 56 to thus prevent elevation of the tucker blade and advance of the books resting on the delivery table 42.

If the feeler is held against dropping down into the slot 9, as by a stitched book on the saddle as shown in Figure 1A, counter-clockwise rotation of the shaft 38 and the bell crank lever 50 is limited. By so restraining the bell crank lever against further counter-clockwise rotation, the latch 53 is held against dropping down into its keeper recess 56 whereupon the combined latching bar and driving link 55 is free to move to the right as the roller 64 follows the low portion of the delivery cam 27.

Thus it will be seen that whenever the feeler 36 is held against dropping down into the slot 9 the latch 53 is held out of its keeper recess 56 and the mechanism is free to operate in the normal manner to effect delivery of the stitched book which held the feeler from dropping into the slot 9 and also to effect intermittent advance of the seriated bank of books resting on the delivery table 42.

The manner in which the books are lifted into the bite of the delivery rolls 11-12 has already been described and as will be readily apparent once the book is in the bite of these rolls their continuous rotation carries the book upwardly to be deflected by a guide 71 onto the delivery table 42. As is customary, the delivery table comprises an endless apron formed by a plurality of side-by-side endless belts 72 (only one of which is shown) trained over suitably mounted pulleys to be intermittently advanced by a pawl and ratchet mechanism indicated generally by the numeral 73, and actuated by the rocking motion of the compound lever 58.

The driving shaft 74 for the delivery belts has a ratchet wheel 75 fixed thereto with which two pawls 76 and 77 coact. The pawl 76 is pivoted on one end of a lever 78 which in turn is medially pivoted on the shaft 74, and the other end of the lever 78 is connected with the arm 60 of the com-

pound lever 58 through a link 79. Thus the rocking motion of the compound lever 58 is imparted to the lever 78, and the range of this motion is such that during each cycle of the machine the pawl 76 will be advanced and retracted a distance slightly greater than the pitch of the ratchet wheel 75 to advance the wheel one tooth.

The pawl 77 is pivoted on a lever 80 which is also rocked about the shaft 74 by the compound lever 58 acting through the link 55. The lever 58 thus provides a common driver for both pawls, but since the motion imparted to the link 55 is greater than that given the link 79 and the connection of the link 55 to the lever 80 is closer to the axis of the shaft 74 than the connection between the lever 78 and the link 79, the throw of the pawl 77 is greater than that of the other pawl 76. Actually, in the present instance it is twice that of the pawl 76.

However, the pawl 77 is normally masked or held out of engagement with the teeth of the ratchet wheel 75 by a lock-out roller 81 on the free end of a pivoted lever 82. This roller 81 lies between the pawl 77 and a hub 83 on the ratchet wheel 75, the diameter of the hub being sufficient to hold the pawl 77 out of engagement with the ratchet wheel except when a notch 84 in the hub aligns with the lock-out roller 81.

A comparison of Figures 8, 9 and 10 illustrates the manner in which the lock-out roller 81 masks the pawl 77 through the greater portion of rotation of the ratchet wheel but permits the pawl 77 to engage the ratchet wheel once each revolution thereof. Thus since the throw of the pawl 77 is twice that of the pawl 76 it advances the ratchet wheel two teeth once each full rotation of the ratchet wheel.

By virtue of this long advance of the delivery belts once each complete rotation of the ratchet wheel the counting of the books as they are taken off the delivery table is facilitated since the seriated bank of books thereon will be divided into groups of equal number which, in the present instance, is ten.

It is, of course, to be understood that the pawls 76 and 77 are yieldingly biased into engagement with the teeth of the ratchet wheel, and to hold the lock-out roller 81 against the underside of the hub 83 and cause it to ride into the notch 84 the lever 82 is yieldingly urged upwardly by a tension spring 85. It should also be noted that to enable the lock-out roller 81 to hold the pawl 77 out of engagement with the teeth of the ratchet wheel this pawl is wider than the ratchet wheel as will be seen in Figure 5.

Though no doubt apparent from the directly foregoing description it is desirable to note that since the compound lever 58 provides a common driver for both pawls, the engagement of the latch 53 in consequence to the feeler 36 dropping down into the slot 9, precludes operation of both pawls as well as ascent of the tucker blades.

Attention is directed to the fact that since the bell crank lever 50 which is loose on the shaft 38 and the lever 43 which is fast on the shaft 33 are yieldingly held together by the tension spring 86, these two levers normally move in unison. However, if the latch 53 has been engaged with its keeper recess 56 as a result of the feeler 36 dropping down into the slot 9, subsequent positive clockwise rotation of the lever 43 imparted thereto by the feeler cam 26 acting through the lever 47 lifts the feeler without affecting the position of the bell crank lever 50 and conse-

quently the engagement of the latch 53 in its keeper recess 56. In this case the levers 43 and 50 merely move relatively to each other against the tension of the spring 86.

If during the next cycle of the machine a stitched book is advanced to delivery position at which it blocks descent of the feeler into the slot 9 (as in Figures 1 and 1A) the spring 86 will swing the lever 50 clockwise the distance permitted by the adjustment of the screw 48 as soon as the tension on the latch 53 is relieved by leftward movement of the link 55 as the high point on the delivery cam 27 passes over the cam follower 64. With this spring actuated movement of the bell crank lever 50 the latch 53 is lifted out of its keeper recess 56, the screw 48 enabling the relationship between the latch and its keeper to be adjusted to the proper setting.

As noted hereinbefore, the arm 37 which carries the feeler is adjustable lengthwise of the shaft 38. Consequently the feeler may be located at any point along the length of the saddle so as to assure its being properly positioned regardless of the length of the signatures being handled. Also, by this simple expedient of adjusting the position of the feeler location the machine may be adapted for so-called "two-up," "three-up," or even "four-up" work. Figure 12 diagrammatically illustrates "two-up" operation of the machine.

In this case the book is approximately twice the length that can be adequately encompassed by the stitcher heads, but in view of the fact that the ascent of the tucker blades can be restrained until the feeler 36 dictates the operation thereof, and since the feeler location has been adjusted to "two-up" operation, the first half of the book may be stitched during one cycle, or as indicated in Figure 12, during position No. 1 and then during the next cycle, position No. 2, the rear half of the book is stitched. Two successive cycles of the machine are thus devoted to the stitching of a single book. During the next cycle of the machine when the book is advanced to position No. 3 it is wholly in the delivery mechanism and the feeler 36 has been kept from dropping down into the slot 9 whereupon the mechanism functions to effect the delivery of the fully stitched book.

With the machine in operation and stitched books following one right behind the other a book will be delivered every other cycle of the machine on such "two-up" work, but if by chance an hiatus occurs in the presentation of the groups of signatures to the stitcher heads and delivery mechanism, the feeler 36 dropping down into the slot 9 will preclude operation of the tucker blades and the delivery belts until a book is again in proper delivery position.

It is, of course, to be understood that the stroke of the gripper fingers 6 and the gripper bar with which they coact is adjustable and may be set or fixed at any desired length within the range of the machine.

From the foregoing description taken in connection with the accompanying drawings it will be readily apparent to those skilled in the art that the book or signature stitching machine of this invention possesses a valuable advantage over such machines of the past since it enables the machine to be quickly and easily adapted for "one-up" and "two-up" and, if necessary, even "three-up" or "four-up" work; that it facilitates manual counting of the books taken from its delivery table; and assures proper coordination be-

tween the removal of the books from the saddle and the intermittent advance of the delivery belts, both regular and long, by having all three of these functions controlled by the same feeler.

What I claim as my invention is:

1. In a book stitching machine of the character described: a saddle upon which stitched books rest preparatory to delivery from the machine; an endless book supporting apron onto which books lifted from the saddle are discharged; means for lifting a book from the saddle and discharging it onto the apron, said means including a tucker blade movable upwardly through the saddle; pawl and ratchet mechanism for intermittently advancing the apron a short distance with each discharge of a book onto the apron, said intermittent advance of the apron effected by said pawl and ratchet mechanism being in uniform increments; other pawl and ratchet mechanism for periodically advancing the apron a greater distance so that books deposited upon the apron are arranged in groups spaced apart a greater distance than the uniform spacing of the books in each group; a feeler positioned to feel for a book on the saddle; and mechanism controlled by the feeler arresting operation of the tucker blade and both pawl and ratchet mechanisms so that removal of a book from the saddle and all advance of the apron are dependent upon the same controlling condition.

2. In a book stitching machine of the character described, the combination of: a saddle to support groups of signatures to be stitched and books produced by the stitching of such signatures; stitcher heads positioned above the saddle for stitching groups of signatures presented thereto; a tucker blade mounted for movement upwardly through the saddle at a distance downstream from the stitchers to lift stitched books off the saddle; a spring biasing the tucker blade upwardly; means for positively retracting the tucker blade each cycle of the machine; means reciprocable along the saddle for advancing groups of signatures to a stitching position under the stitcher heads and for advancing stitched books to a delivery position on the saddle above the tucker blade, said means having a predetermined stroke and operating to effect an advance of the signatures and books on the saddle a fixed distance once each cycle of the machine so that books no longer than said predetermined stroke can be fully stitched during one cycle, advanced to the delivery position and lifted off the saddle by the tucker blade during the next cycle while books longer than said predetermined stroke can be adequately stitched by devoting two or more successive cycles to the stitching operation and restraining the ascent of the tucker blade until the book has been fully stitched and wholly advanced to the delivery position; latch means biased to an engaged position restraining the tucker blade against spring produced upward movement from its retracted position; latch controlling detector means for detecting the presence of a book on the saddle; means for mounting said detector means at any point along that portion of the saddle which might be occupied by a book in the delivery position so that the detector means is positionable to detect a fully stitched book directly upon advance of the entire book wholly into the delivery position regardless of the number of cycles required to stitch the book; and an operative connection between the detector means and the latch means and through which the latch means is

disengaged to effect spring produced upward movement of the tucker blade whenever the detector means detects a book on the saddle but is left engaged during those cycles of the machine when no book is present to be detected by the detector means.

3. In a book stitching machine of the character described, the combination of: a saddle to support groups of signatures to be stitched and books produced by the stitching of such signatures; stitcher heads positioned above the saddle for stitching groups of signatures presented thereto; a tucker blade mounted for movement upwardly through the saddle at a distance downstream from the stitchers to lift stitched books off the saddle; a spring biasing the tucker blade upwardly; means for positively retracting the tucker blade each cycle of the machine; means reciprocable along the saddle for advancing groups of signatures to a stitching position under the stitcher heads and for advancing stitched books to a delivery position on the saddle above the tucker blade, said means having a predetermined stroke and operating to effect an advance of the signatures and books on the saddle a fixed distance once each cycle of the machine; latch means biased to an engaged position restraining the tucker blade against spring produced upward movement from its retracted position; a feeler for controlling the latch means; motion transmitting and controlling linkage operatively connecting the feeler with the latch means; said linkage including a rock shaft upon which the feeler is mounted and by which it is moved toward and from the saddle to feel for books on the saddle, said rock shaft extending lengthwise of the saddle at that portion thereof adjacent to the tucker blade; and means securing the feeler to the rock shaft at any point along the length thereof so that the feeler may be positioned to feel for a completely stitched book directly upon presentation thereof wholly into the delivery position regardless of the number of cycles required to stitch the book and whereby the tucker blade may be held inoperative during certain cycles of the machine and books longer than can be adequately stitched during one cycle of the machine may be handled by devoting more than one cycle to the stitching thereof.

4. In a book stitching machine: a saddle along which stitched books are advanced to a delivery position; a delivery table including a movable apron; mechanism including a tucker blade for lifting a stitched book off the saddle and discharging it onto the movable apron; pawl and ratchet means for intermittently advancing the apron; a cam operating in timed relation with said mechanism; a motion transmitting connection between the cam and the pawl of said pawl and ratchet means for positively advancing the pawl; a spring acting upon said motion transmitting connection for impositively retracting the pawl, the timing between the operation of the tucker blade and the cam coordinating the intermittent advance of the apron with the discharge of the books onto the apron; a latch engageable with said motion transmitting connection to restrain the same against spring produced motion; a feeler movable toward and from the saddle and positioned to detect a book in delivery position on the saddle above the tucker blade to have its motion toward the saddle arrested by a book in such position but movable beyond its book engaging position whenever no book is present on

the saddle to arrest the motion of the feeler; and mechanism operatively connecting the feeler with the latch and operable in consequence to movement of the feeler beyond its book engaging position to effect engagement of the latch.

5. In a book stitching machine of the character described: a saddle along which books are advanced to a book stitching position; a tucker blade movable upwardly through a portion of the saddle defining a delivery position and located a distance downstream from the stitching position, to lift a stitched book therefrom; mechanism for advancing the books along the saddle from the stitching position to the delivery position; a delivery table including a movable book supporting apron; means for transferring a stitched book from the tucker blade to said apron; pawl and ratchet mechanism for intermittently advancing the apron; a continuously rotating cam; a latch operable to restrain upward movement of the tucker blade; a motion transmitting connection between the cam and the pawl and ratchet mechanism; a motion transmitting connection between the cam and said latch; an element common to said two motion transmitting connections and having a cam follower through which the cam acts to positively advance the pawl and control the position of the latch; a spring acting upon said common element to cause it to follow the cam and in doing so to impositively retract the pawl and disengage said latch; a second latch operable to restrain said common element against spring produced cam permitted movement to thereby preclude retraction of the pawl and disengagement of the tucker blade latch; a feeler movable toward and from the saddle and positioned to detect a book in the delivery position on the saddle to have its motion toward the saddle arrested by a book thereon but movable beyond its book engaging position whenever no book is present on the saddle to arrest the motion of the feeler; and mechanism operatively connecting the feeler and said second latch and operable in consequence to movement of the feeler beyond its book engaging position to effect engagement of the second latch and thereby prevent disengagement of the tucker blade latch.

6. In a book stitching machine: a saddle upon which stitched books are supported; a tucker blade movable upwardly through the saddle to lift the stitched books off the saddle; a latch movable to and from an engaged position restraining upward movement of the tucker blade; a spring biasing the latch to its engaged position; a continuously rotating cam; a pivoted lever having a cam follower riding on said cam; a motion transmitting connection between said lever and the latch operable during movement of the lever in following the low portion of the cam to disengage the latch; a spring acting upon said lever to normally cause the same to follow

the cam; a second latch movable to and from an engaged position restraining spring produced motion of the lever; a feeler movable toward and from the saddle and positioned to feel for a book thereon to have its motion toward the saddle arrested by a book on the saddle but movable beyond its book engaging position whenever no book is present on the saddle to arrest motion of the feeler; and mechanism operatively connecting the feeler with said second latch and operable in consequence to movement of the feeler beyond its book engaging position to effect engagement of said second latch.

7. In a book stitching machine of the character described: a saddle along which signatures to be stitched and the stitched books are advanced; a cam operated delivery mechanism including a tucker to lift stitched books off the saddle; a lock-out latch movable to and from an engaged position restraining said mechanism against operation; a rock shaft parallel to the saddle; a feeler fixed to the rock shaft to be swung by oscillation of the rock shaft laterally toward the saddle and past the same if no book is present thereon to arrest the feeler; a rotatable cam; means including a cam follower riding on the cam and a spring, for translating rotation of the cam into oscillation of the rock shaft in a direction such that the feeler is positively swung away from the saddle and impositively moved toward the saddle; a lever pivoted to rock about the axis of the rock shaft; a motion controlling connection between said lever and the lock-out latch through which the position of the lever governs engagement of the lock-out latch; and a motion transmitting connection between said lever and the rock shaft through which movement of the rock shaft in consequence to failure of a book to arrest the impositive movement of the feeler effects movement of the lever to a position at which it causes engagement of the lock-out latch.

ELMER W. BELLUCHE.
